UNITED STATES PATENT OFFICE.

JAMES L. MALLERY, OF GRANTS PASS, OREGON.

DESIGN FOR A BADGE.

SPECIFICATION forming part of Design No. 36,943, dated June 7, 1904.

Application filed April 25, 1904. Serial No. 204,913. Term of patent 7 years.

To all whom it may concern:

Be it known that I, JAMES L. MALLERY, a citizen of the United States, and a resident of Grants Pass, in the county of Josephine and 5 State of Oregon, have invented a new, original, and ornamental Design for a Badge, reference being had to the accompanying drawing.

The figure is a plan view of a badge, showing my new design.

What I claim as new, and desire to secure by Letters Patent, is—

The ornamental design for a badge, as shown.

JAMES L. MALLERY.
